Patented Oct. 22, 1918.

Inventor,
Britton E. Byrd,
By his Attorneys,
Mayers, Cushingman & Rea.

UNITED STATES PATENT OFFICE.

BRITTON E. BYRD, OF DURHAM, NORTH CAROLINA, ASSIGNOR TO MILLS DEVICES COMPANY, OF DURHAM, NORTH CAROLINA, A CORPORATION OF NORTH CAROLINA.

KNOTTER.

1,282,041.

Specification of Letters Patent. Patented Oct. 22, 1918.

Application filed April 5, 1918. Serial No. 226,824.

To all whom it may concern:

Be it known that I, BRITTON E. BYRD, a citizen of the United States, residing at Durham, in the county of Durham and 5 State of North Carolina, have invented new and useful Improvements in Knotters, of which the following is a specification.

This invention relates to certain novel and useful improvements in knotters and 10 has particular application to a manually operated knotting device adapted to be employed for the purpose of securing together the ends of threads, provision being made for temporarily but securely attaching the 15 device to a hand of the operator.

In the present instance, it is my purpose to provide a knotting device of this type composed of but relatively few parts which are so constructed and correlated as 20 to rapidly, positively, efficiently and securely tie the knot and to sever the ends of the threads adjacent the knot.

Furthermore, I propose to provide a knotter wherein the parts are of exceedingly 25 compact construction and of such character that they may be stamped or otherwise formed from sheet metal, thus dispensing with the use of expensive and tedious machine work and skilled labor, and thereby 30 reducing the cost of production of the device to a minimum.

Another object of the invention is a provision of a knotter wherein the parts may be readily and quickly assembled, and 35 are so few in number that the complete device is a far simpler mechanism than the complicated prior devices of this general character with which I am acquainted, and, in addition to this, my knotter from the 40 standpoint of structure, possesses advantages of stability, durability, and freedom from derangement not ordinarily incident to the usual form of knotter.

It is also my purpose to provide a device 45 of this character which may be sold to the ultimate purchaser at a relatively low cost.

With the above recited objects and others of a similar nature in view, my invention consists in the construction, combination and 50 arrangement of parts set forth in and falling within the scope of the appended claims.

In the accompanying drawings:

Figure 1 is a view in side elevation of a knotter embodying my invention.

Fig. 2 is a perspective view thereof look-

ing at the device from the opposite side to that shown in Fig. 1.

Fig. 3 is a perspective view with the casing cap removed.

Fig. 4 is a view in side elevation of substantially so much of the structure as is shown in Fig. 3, and showing the tying bill and the operating thumb lever therefor in normal position.

Fig. 5 is a similar view to that shown in Fig. 4 and showing the thumb lever in its depressed position after the knot has been tied and the thread stripped.

Fig. 6 is a detail view indicating both the open and closed positions of the tying bill.

Fig. 7 is a vertical sectional view taken through the assembled knotter such as is shown in Figs. 1 and 2.

Fig. 8 is a detail perspective view of one of the side plates of the knotter looking at the inner face of such plate.

Fig. 9 is a perspective view of the supporting arm which is carried by the grip or handle.

Referring now to the accompanying drawings in detail, the numeral 1 indicates the handle or grip of the device which is in the nature of a flat plate provided with an angular end 2, while 3 is a strap connecting the ends of the grip and serving to fasten the device onto the hand of the operator. This grip 1, like other parts of the device, is preferably stamped or otherwise formed from sheet metal so that the entire structure may be economically manufactured. Preferably formed integral with the grip 1 is a curved supporting arm 4, the upper free end of which has an elongated perforation 5. At this free end of the arm 95 is carried the casing A, which contains and embraces certain of the operating parts of the device. This casing A includes a stationary side plate 6 and a detachable cap 7, the latter embracing the side plate 8 and the 100 circular wall 9 fast with the side plate 8. The stationary side plate 6 is formed at its upper end with a straight edge 10 from which extends the offset upwardly projecting thread holding arm 11, which is in the nature of a 105 hook. Likewise the side plate 8 of the cap 7 is formed with an upwardly extending thread guide 12 also in the nature of a hook which is bent or distorted outwardly, as shown in Fig. 7. The side plate 6 which 110

is shown in detail in Fig. 8 is provided with a central aperture 13 through which projects the flattened shank 14 of the screw bolt 15, this flattened shank 14 also passing 5 through the elongated slot 5 at the end of the arm 4 and is fastened by means of the thread nut 16, while 16^a is a pin extending inward from the arm 4 and through the aperture 16^b in the side plate 6, so that the 10 latter is held stationary or against rotation relative to the arm 4. The head of the bolt 15 is in the nature of a flat disk shown at 17 and bears against the vertical wall 18 of the bracket 19 for the tying bill. This wall 18 is formed with a central bolt opening. 15 The bolt 14 thus holds the wall 18 of the bracket 19 flat against the inner face of the side plate 6 of the casing, but the bracket may partially rotate or turn on the bolt 20 along with the cap 7 as hereinafter set forth. Extending from this inner face of the side plate 6 of the casing A is a semi-circular or curved rack 20, while 21 indicates a segmental slot formed in this side plate 6, 25 and which slot extends slightly beyond the upper end of the rack 20.

The tying bill of the knitter is shown at 22 and comprises a tubular shaft 23 preferably formed of a single piece of rolled 30 metal having spaced slots 24 extending circumferentially of the lower end portion thereof, and which slots are adapted to be engaged by the teeth of the rack 20 during the rotation of the tying bill of the shaft much 35 after the manner of a rack and pinion mechanism. The upper end of this tubular shaft 23 is formed to constitute a bifurcated bill shank which terminates in the two hook members 25, and between which members 40 is pivoted the thread tying and cutting bill 26 which is of the usual construction and operates in the usual manner well understood in devices of this class. The bill 26 is opened and closed, during its rotation and 45 oscillation by the contact of its blade 26^a with the wall of the relatively large opening 27 in the upper section 28 of the U-shaped plate 29, which is the upper part 50 of the tying bill bracket, this opening 27 being arranged eccentrically to the bearings of the bill shaft. In the lower section 31 of the plate 29 is an opening 30 which is of just sufficient dimensions for the passage of 55 the tying bill shaft, the latter also passing through an alining opening 32 in the foot plate 33 of the bracket 19, the walls of these 60 plate apertures forming the bearings for the bill shaft. The upper section 28 of the bracket has an extension 34 which forms a thumb lever for operating the knitter as 65 hereinafter described. When this thumb lever is actuated, the tying bill bracket with its tying bill, as well as the casing cap, will be oscillated relative to the stationary side plate 6, the bracket turning on the shank

14 of the bolt 15. The vertical wall 18 of this bracket through which the bolt 15 projects is provided with an outwardly extending stud 35, which projects through the segmental slot 21 in the side plate. Pivoted 70 on the exterior portion of the stud 35 is a bifurcated thread clamp 37 which is formed from a single piece of metal folded to form duplicate members, this thread clamp being approximately segmental in 75 shape in its general contour and has its upper free end formed with fingers 38 which lie one at each side of the thread holding hook or arm 11 so as to embrace the latter. This thread clamp 37 cooperates with this 80 thread holding arm 11 to both clamp the thread and to subsequently assist in stripping the same from the tying bill.

The above is a description of the structural features of my knitter, and I will 85 now briefly describe one manner in which the parts may be assembled. The tying bill bracket is placed with its vertical wall 18 in contact with the inner face of the side plate 6 of the casing and with the upper section 90 28 of the bracket in approximate alinement with the straight edge of the plate 6, so that the bolt openings in the centers of the wall 18 and the plate 6 will register. The bolt shank 15 is now inserted through these 95 registering central openings to temporarily connect the bracket with the side plate 6. The tying bill shaft may now be mounted in the bracket by inserting it through the openings in such bracket to cause the spaced 100 slots 24 in the shaft to be engaged by the teeth of the rack 20, so that the shearing or thread cutting bill will be positioned to be opened or closed by the circular wall of the opening 27. The thread clamp 37 may now 105 be applied by being pivotally mounted upon the stud which projects from the tying bill bracket and through the segmental slot 21, the clamp being so positioned that the upper 110 clamping fingers thereof will lie one at each side of the thread holding arm 11. The coiled tension spring 39 may now be positioned about the projecting end of the bolt shank and fastened at its terminals to the pivoted clamping member and to the stationary supporting arm 4, the purpose of 115 this spring being to return the parts to normal position after each thread tying operation. The nut 16 may then be threaded onto the projecting end of the bolt shank so that 120 the parts thus far described are now assembled on the stationary side plate 6. The cap 7 of the casing A may now be applied, and this cap as will be seen by reference to Fig. 2 has its side plate section 8 formed with 125 an upper relatively wide oblong slot 40 through which projects the bight or looped portion of the bracket 29, and likewise this side section 8 of the cap is formed with a lower relatively narrow elongated slot 41 130

through which projects the foot plate 33 of the bracket. A locking member 42, in the present instance in the nature of a wire loop or pin may now be passed through the projecting bight of the upper section of the bracket and hooked through an opening in the foot plate so as to firmly secure the parts together as will be understood by reference to Fig. 2.

10 The knotter is now ready for operation and as the manner of employing these knotters is well understood, I will make but brief reference to the same in the present instance. The ends of the thread to be knotted are placed as usual so as to lie beneath the hooked thread guides or thread holding arms and so as to pass beneath the tying bill. The lever is now depressed against the action of the coiled spring by the operator 15 pressing the thumb against the lever and this will result in the giving to the bill a rotary movement due to the circular rack operating on the bill shaft and at the same time the bill with its bracket and also the 20 casing cap will be moved in a path of travel downward and backward relative to the stationary side plate 6 as shown in Fig. 5. In a word, as the cap section of the casing with the tying bill bracket and the bill itself are 25 all rotatably mounted relative to the stationary side plate 6 of the casing by means of the bolt 14 such cap section and its connected parts including the bill, will be swung by the pressure of the operator's 30 thumb from the position shown in Fig. 2 to that indicated in Fig. 5. The character of the knot formed and the thread shearing or cutting operation will be understood by reference to my earlier Patent, No. 870,527, 35 dated November 5, 1907. At the first part of this rotation and oscillation of the bill, the latter which is closed, will take up slack to form a loop in the threads and the continued movement of the bill will cause 40 the latter to gradually open and assume its shearing position as is common in devices of this sort. At the same time, the clamp 37 will rise to clamp the threads, while the slack is taken up by the downward and 45 rearward movement of the thread guide 12 carried by the oscillating cap and the knot is tied. After the knot is tied, the bill will close to cut the ends of the threads and the knotted thread will be stripped from the bill. 50 Upon the operator releasing pressure upon the thumb lever, the spring will return the parts to normal position.

It will be seen that as distinguished from the usual knotters of this class, I cause the 55 tying bill as well as one of the thread guides to oscillate in addition to giving the bill the usual rotary movement, and this oscillation of the bill and guide takes place relative to the thread holding and thread 60 clamping members carried by the stationary

side plate. And, furthermore, in the thread clamping members at the stationary side plate, the slight upward and forward movement due to the segmental slot and the stud of the clamp working therein will cause the 70 thread to be first clamped during the knot tying operation and then stripped from the tying bill after the knot has been tied.

It will also be noted that all of the parts of my device may be made very economi- 75 cally as they can be stamped or otherwise formed from sheet metal and that as compared with the complicated relatively cumbersome knotters now in use, this device presents a comparatively small light con- 80 struction which may be easily manipulated to tie the knots.

While I have herein shown and described one particular embodiment of my invention, I wish it to be understood that I do not confine myself to all the precise details of construction herein set forth by way of illustration, as modification and variation may be made without departing from the spirit 85 of the invention or exceeding the scope of 90 the appended claims.

What I claim is:-

1. In a knotting device, the combination with a support adapted to be attached to a hand of the operator, of a member stationary with the support and provided with a thread holding arm, thread clamping means pivotally associated with said member and movable relative to the thread holding arm, a casing cap associated with the stationary 95 member to form a complete casing therewith, said cap having a thread guide, a tying bill interposed between the thread guide of the cap and thread holding arm of the stationary member, and operating means for 100 rotating the tying bill and for simultaneously oscillating the cap and the said tying bill.

2. In a knotting device, the combination of a support, of a side plate stationary 110 therewith and provided with a thread holding arm, a bolt extending through said plate, a bracket mounted to turn on said bolt, a thread clamp connected with said bracket and associated with and movable relative to 115 the thread holding arm of the side plate, a tying bill rotatably mounted in the bracket, a cap provided with a thread guide, operating means for rotating the tying bill and simultaneously bodily swinging said bill and 120 the cap with its thread guide, and means for returning the parts to normal position.

3. In a knotting device, the combination of a supporting arm, a plate member stationarily mounted thereon and having a 125 thread holding arm, a thread clamp associated with the thread holding arm, a tying bill bracket mounted to turn relative to the stationary plate, a tying bill mounted to rotate in said bracket, means including a 130

2: curved rack engaging spaced slots in the shaft of the tying bill for rotating the latter in the bracket, a cap connected with said bracket and provided with a thread guide, and means for turning the bracket to bodily swing the cap and its tying bill, and means for returning the bracket with the cap and tying bill to normal position.

4. In a knotting device, the combination 10 with a supporting arm, of a casing associated therewith and comprising a stationary section and a bodily movable section, a thread holding member carried by one of said sections, a thread clamp associated with 15 the thread holding member, a thread guide carried by the other section, a tying bill, and means for actuating the tying bill and simultaneously moving the bodily movable section of the casing relative to the stationary section of such casing.

5. In a knotting device, the combination 20 of a casing comprising a stationary section and a movable section, said stationary section having thread holding and clamping 25 means, said movable section having a thread guide, a rotatable tying bill, means for imparting a rotary movement to the tying bill and an oscillating movement to said bill and to the movable section of the casing.

6. In a knotting device, the combination 30 of a support adapted to be carried on the hand, a casing including two sections, one of which is movable relative to the other, thread holding and clamping means carried 35 by one of said sections, a thread guide carried by the other section, a tying bill, and means for rotating and oscillating the tying bill and simultaneously oscillating one of the sections of the casing relative to the other section of such casing.

7. In a knotting device, the combination 40 of a support adapted to be carried on the hand, a casing, a tying bill bracket mounted to turn relative to one side of the casing, said 45 bracket having portions projecting through the opposite side of the casing, means for locking the bracket to the last mentioned side of the casing, whereby the casing will be assembled, thread holding and clamping 50 means carried by one side of the casing, a thread guide carried by the other side of the casing, and a tying bill operatively associated with the thread holding and clamping means and the thread guide.

8. In a knotting device, the combination 55 with a support adapted to be carried on the hand, of stationary thread holding means, pivoted thread clamping means associated with the thread holding means, a knot tying 60 bill and thread guiding means both normally located substantially in lateral alinement with the stationary thread holding means, means for rotating the knot tying bill, and means for oscillating both the thread guide

and the knot tying bill relative to the stationary thread holding means.

9. In a knotting device, the combination 65 with a support adapted to be carried on the hand, of an arm projecting from said support, a cylindrical casing carried by said arm and including a stationary side plate and an oscillating side plate, thread holding 70 and clamping means carried by one of said plates, a thread guide carried by the other of said plates, a tying bill located between the two plates of the casing, and means for simultaneously oscillating both the tying bill and the oscillating side plate of the casing.

10. In a knotting device, a cylindrical 80 casing having opposed side plates, each provided with a projecting thread engaging hook, a tying bill located between the side plates and normally positioned substantially in lateral alinement with the hooks thereof, 85 means for rotating the tying bill, and means for simultaneously swinging said bill and one of the side plates relative to the other side plate.

11. In a knotting device, a cylindrical 90 casing having a pair of opposed substantially circular side plates, each provided with an integral thread engaging hook, one of said plates being movable relative to the other, and a rotatable tying bill operatively associated with said hooks.

12. In a knotting device, a cylindrical casing including a pair of side plates, each having a projecting thread engaging hook, a thread clamp associated with one of said 100 hooks, a rotating tying bill interposed between said plates, and means for swinging the tying bill and one of said plates relative to the other plate.

13. In a knotting device, a support, and a shaft carried thereby, a stationary plate mounted on the shaft and having a thread engaging hook, a bracket mounted to swing on said shaft and including a disk through which the shaft projects, and spaced laterally extending portions projecting from said disk, a tying bill journaled in the laterally projecting portions of the bracket, a rack engaging with a portion of the tying bill for rotating the latter, a swinging plate 110 connected to and swinging with the bracket, and a finger plate projecting from the bracket and adapted to be manipulated to simultaneously swing the bracket, the tying bill and the swinging plate.

14. In a knotting device, the combination 115 with a support adapted to be attached to the hand of an operator, of a member stationary with the support and provided with a thread holding arm terminating in a thread engaging hook, a thread clamping member pivotally associated with the stationary member 120 and movable relative to the thread holding

- arm, said clamping member having a pair of terminal fingers lying one at each side of the hook of the thread holding arm, a swinging thread guide normally positioned 5 opposite the thread holding arm and also having a thread engaging hook, a rotating tying bill located between and in spaced relation to the thread holding guide and the thread holding arm, means for rotating the 10 tying bill, and means for simultaneously swinging both the thread guide and the tying bill relative to the thread holding arm.
15. In a knotting device, a support adapted to be carried on the hand, an arm extending from said support, a shaft carried by said arm, a casing including a pair of side plates, one of which plates is mounted on the shaft and held secured against movement thereon, a thread engag-
- ing hook projecting from the stationary side 20 plate, a bifurcated thread clamp pivotally associated with said stationary side plate and embracing the hook of the latter, a segmental rack extending from the exterior wall of the stationary side plate, a bracket 25 mounted to turn on the shaft, a tying bill journaled with the segmental rack whereby said tying bill may be rotated, a movable side plate for the casing connected with said bracket and turnable therewith, a thread 30 guide on the movable side plate and a finger piece projecting from the latter and operable to turn the bracket and movable side plate and to swing the tying bill.
- In testimony whereof I have hereunto set 35 my hand.

BRITTON E. BYRD.
